P. R. DRENNING

SIDE FRAME AND JOURNAL BOX MOUNTING

Filed Oct. 7, 1926

UNITED STATES PATENT OFFICE.

PERCY R. DRENNING, OF BALTIMORE, MARYLAND, ASSIGNOR, BY MESNE ASSIGNMENTS, TO T. H. SYMINGTON AND SON, INC., OF BALTIMORE, MARYLAND, A CORPORATION OF MARYLAND.

SIDE-FRAME AND JOURNAL-BOX MOUNTING.

Application filed October 7, 1928. Serial No. 140,182.

The invention relates to side frames and journal box mountings forming part of railway car trucks particularly adapted for use in connection with freight cars.

5 The principal object of the invention, generally stated, is to provide a side frame having spring means for mounting the journal boxes thereon, the spring means acting to reduce car roll, eliminate vertical "jiggle" 10 and increase the present spring capacity of trucks.

An important object of the invention is to provide a side frame in which the journal boxes are supported by purely flexible means, 15 there being an absence of rigid connection between the journal boxes and the major portion or relatively stationary part of the side frame so as to obtain the maximum resilience for accomplishing the desired results.

20 The object of the invention, more specifically stated, is to provide a side frame having cantilever spring means for supporting the journal boxes with respect to the rigid portion of the side frame, in combination with 25 other supporting means acting to prevent movement of the journal boxes in any direction other than vertical.

A specific object of the invention is to provide novel means for securing the cantilever 30 springs to the rigid portion of the side frame.

Another object of the invention is to provide a truck side frame embodying a central rigid portion within which is mounted the bolster supported by the usual springs, and 35 further including journal boxes connected at their tops with the outer ends of cantilever springs secured to the main or rigid portion of the side frame and connected at their bottoms with members pivoted to the rigid portion 40 of the side, said last named connecting members or pivoted connecting members being adapted to flex and assist the cantilever springs during vertical movement of the journal boxes with respect to the rigid portion 45 of the side frame during car travel.

Still another object of the invention is the provision of a side frame of this character in which the journal boxes are so mounted with respect to the rigid portion of the side frame 50 as to prevent any play whatsoever other than the desired vertical movement, the absence of play preventing undue wear and crystallization as might occur as the result of striking of the parts together.

Still another object of the invention is to provide a truck side frame of this character or embodying these features which might be so constructed and arranged as to be capable of installation within trucks to replace rigid side frames of conventional pattern without it being necessary to redesign the entire truck structure. 55

An additional object of the invention is the provision of a structure of this character which will be comparatively simple and inexpensive to manufacture, positive in action, efficient and durable in service, and a general improvement in the art. 60

With the above and other objects and advantages in view the invention preferably 70 consists in the combination and arrangement of parts and the detailed formation to be hereinafter more fully described and claimed and illustrated in the accompanying drawings in which:

Figure 1 is a side elevation of a truck side frame constructed in accordance with the invention, a portion of the rigid or central frame member being in section and one journal box and support therefor being omitted. 80

Figure 2 is a vertical cross sectional view taken on the line 2-2 of Figure 1, looking in the direction of the arrows and showing one means for securing the cantilever springs to the rigid portion of the frame. 85

Figure 3 is a fragmentary longitudinal sectional view showing a modified means for securing the cantilever springs in position.

Referring more particularly to the drawings, the numeral 1 designates the rigid or 90 central portion of the side frame conveniently formed as either a casting or forging. The exact shape of this frame 1 may be varied within wide limitations though in the present instance it is represented as being substantially rectangular with a curved lower portion 2 providing a species of truss for strengthening the structure. Any specific arrangement of reinforcing ribs, webs and the like may be provided as may be found desirable in actual practice. The frame 1 is provided with the usual window opening 3 within which is adapted to be located the end of the truck bolster, not shown, and the supporting spring, likewise not illustrated, provided for the purpose of supporting the bolster and the load carried thereby. 95

Broadly considered, the structure com- 100

prises the rigid frame member 1, cantilever springs 4 secured to and projecting from opposite sides thereof, journal boxes 5 carried by the outer ends of the springs, and supporting members 6 connected with the frame 1 and with the journal boxes, this arrangement permitting vertical movement of the journal boxes with respect to the frame 1 while preventing movement in any other direction.

10 While it is conceivable that various means might be provided for mounting the cantilever springs 4, I have shown the upper portion or corners of the frame 1 as formed with pockets or sockets 7 which preferably terminate short of the window opening to leave partition walls 8 constituting abutments for the ends of the springs, the corners of the frame 1 being preferably formed with extensions 9 provided for the purpose of 15 insuring sufficient bearing areas for the springs. Each spring 4 is shown as comprising a series of plates or leaves 10, all of which are illustrated in the present instance as of progressively decreasing lengths, the longest being at the bottom. However, this is 20 a detail of construction and arrangement which may be varied within the scope of the invention.

While various means might be provided 25 for securing the springs with respect to the frame 1, Figures 1 and 2 illustrate a convenient method of accomplishing this. In these two figures the numeral 11 designates a block extending transversely off the uppermost plate or leaf spring and located within the notch or opening 12 in the top wall of each extension 9. The block 11 is preferably of the same length as the width of the spring upon which it is engaged so that it will fit 30 closely against the opposite sides of the notch or opening 12 to be incapable of longitudinal shifting. Each extension 9 is preferably formed or otherwise provided with laterally extending lugs 13 reinforced by webs 14 and apertured for the passage of the arms of a 35 U bolt 15 which is arranged in inverted position with its bight portion engaged within a groove 16 in the top of the block 11. Suitable nuts 17 are provided on the U bolt beneath the lugs 13 for effecting the proper 40 clamping action so that the springs will be held securely in place and be incapable of accidental disassociation with respect to the frame 1 under all circumstances.

55 Instead of utilizing the above described means for securing the springs to the frame 1, use may be made of the alternative construction such as that illustrated in Figure 3. In this form the spring leaves 10^a are engaged within a socket or pocket 7^a and are held positively against longitudinal movement by a bolt 18 passing through the extension 9^a and through the leaves. The leaves of the spring may be held in clamped engagement with one another by a wedge 19 seating

upon the topmost leaf or plate and having an inclined surface 20 cooperating with an inclined surface 21 at the underside of the top of the pocket or socket, a bolt 22 being provided for forcing the wedge inwardly with respect to the pocket.

70 Regardless of the means provided for securing the springs to the frame 1, the outer ends of the springs carry the journal boxes 5 above described. There is nothing unusual in the construction of the journal boxes and they are shown as having the ordinary covers mounted at 23. A convenient securing means may comprise bolts 24 vertically arranged at opposite sides of each journal box and passing through certain of the spring leaves or plates, these bolts of course carrying nuts 25.

75 To confine the movement of the journal boxes to a vertical direction, I have found it advisable to provide the above mentioned members or supporting means 6 which may conveniently be formed as a suitable length of somewhat flexible spring material, each member being pivoted at 26 upon lugs or ears 80 27 projecting from the frame 1 and being suitably apertured for the passage of the bolts 24, the above mentioned nuts 25 engaging against the underside. The reason for 85 constructing the members 6 of flexible material is that a certain flexure will occur when the journal boxes 5 move relatively to the frame 1. Clearly, the specific pivotal mounting is not material as some arrangement other than that disclosed may be employed, provided the equivalent effect is produced.

90 In the use of the device or structure it will be readily apparent that it is built into a truck in the usual manner and may conceivably replace a side frame of standard or conventional type. The bolster and bolster 95 springs are located within the window opening 3, as is customary, and the journal boxes carry the axles in the usual manner. In actual practice or in the use of the device it will be apparent that a portion of the load on the bolster is supported by the usual truck 100 springs and that the cantilever springs 4 supporting the journal boxes will also operate to take a portion of the load. The period of vibration of the springs 4 is or at least 105 should be different from that of the truck springs so that they will not be synchronized, the result being a reduction in the tendency 110 of the car to develop a roll or side sway, together with the elimination of vertical 115 "jiggle." Obviously, the spring capacity of the truck will be greatly increased so that greater loads may be adequately sustained 120 without any likelihood of damage to any parts of the truck. It is believed that the 125 construction, operation and advantages will be readily apparent to one skilled in the art without further explanation.

130 While I have shown and described a preferred embodiment of the invention and cer-

tain details of formation of the parts, it should be understood that the disclosure is merely an exemplification of the general principles involved and that the right is reserved to make all such changes in the combination and arrangement of parts and the details of construction as will not depart from the spirit of the invention or the scope of the claims hereunto appended.

10 Having thus described my invention, what I claim is:

1. In a truck side frame, the combination of a rigid central frame member, journal boxes located beyond the opposite side edges thereof, and separate spring members carried by said frame member and carrying the respective journal boxes.

2. In a truck side frame, the combination of a central rigid frame member, journal boxes located beyond the opposite side edges thereof in entirely spaced relation thereto, and separate cantilever springs carried by said frame member and secured to the respective journal boxes.

25 3. In a truck side frame, the combination of a rigid central frame member, journal boxes located beyond the opposite side edges thereof in spaced relation thereto, separate cantilever springs secured to the frame member and carrying the respective journal boxes and flexible supporting members projecting from said frame member and secured to the journal boxes.

4. In a truck side frame, the combination of a central rigid frame member, journal boxes located in spaced relation thereto at the opposite side edges thereof, separate banks of elongated plate springs carried by the frame member and engaging upon the tops of the respective journal boxes, and brace members movably mounted upon the frame member at opposite side edges thereof and connected with the bottoms of the journal boxes.

45 5. In a truck side frame, a central rigid frame member, journal boxes located beyond opposite sides of the frame member, cantilever springs rigidly secured to the frame member and secured at the tops of the journal boxes, and supporting members secured to the undersides of the journal boxes and pivoted to the frame member.

6. In a truck side frame, a main frame member of rigid formation provided with sockets at its upper corners, cantilever springs secured within said sockets and projecting beyond the opposite side edges of the frame member, supporting members pivoted to said frame member and projecting beyond opposite side edges thereof beneath and in spaced relation to the springs, and journal boxes mounted between the outer ends of the springs and the outer ends of said supporting members.

7. In a truck side frame, a main frame

member of rigid formation provided with 65 sockets at its upper corners, cantilever springs secured within said sockets and projecting beyond the opposite side edges of the frame member, supporting members pivoted to said frame member and projecting beyond 70 opposite side edges thereof beneath and in spaced relation to the springs, and journal boxes mounted between the outer ends of the springs and the outer ends of said supporting member and rigidly secured thereto. 75

8. In a truck side frame, a rigid frame member, cantilever spring means secured to the upper portion thereof and projecting beyond the opposite side edges thereof, journal boxes secured beneath said spring means at 80 the free ends thereof and vertically movable with respect to said frame member, and movable means rigidly secured to the bottom portions of the journal boxes and connecting the same with said frame to confine the movement of the journal boxes to a vertical direction.

9. In a truck side frame, a rigid frame member formed at its upper corners with 85 sockets and having extensions at the sockets, cantilever springs engaged within said sockets and projecting beyond the side edges of the frame member, means carried by said extensions for securing the springs in the sockets, and journal boxes carried by the free 95 ends of the springs.

10. In a truck side frame, a rigid frame member formed at its upper corners with 100 sockets and having extensions at the sockets, cantilever springs engaged within said sockets and projecting beyond the side edges of the frame member, means carried by said extensions for securing the springs in the sockets, and journal boxes carried by the free 105 ends of the springs and located therebeneath.

11. In a truck side frame, a rigid frame member having a window opening therein for the reception of a truck bolster and bolster supporting springs, said frame member being formed with sockets at its opposite side 110 edges, cantilever springs engaged within said sockets, means carried by said frame member for clamping the springs within the sockets, journal boxes carried by the free ends of the springs, and supporting members secured to 115 the journal boxes and pivoted to said frame member.

12. In a truck side frame, a rigid frame member having a window opening therein for the reception of a truck bolster and supporting springs therefor, said frame member being formed with sockets at its opposite sides, cantilever springs engaged within said 120 sockets, wedge means within the sockets for securing the springs therein, and journal boxes carried by the free ends of the springs.

13. In a truck side frame, a frame member formed with sockets at its opposite side edges,

cantilever springs engaged within said sockets, bolt and wedge means for securing the springs within the sockets, and journal boxes carried by the free ends of the springs.

5. 14. A truck side frame provided at opposite side edges with sockets, cantilever springs having their inner ends located with-

in the sockets, wedge means mounted on the springs and entering the sockets, bolt means for forcing the wedge means into the sockets, and journal boxes secured to the outer ends of the springs. ¹⁰

In testimony whereof I affix my signature.

PERCY R. DRENNING.
